DESIGN FOR A SEAL PRESS OR SIMILAR ARTICLE

Henry E. Sachs and Peter F. Elzi, Denver, Colo.

Application February 1, 1937, Serial No. 67,389

Term of patent 7 years

To all whom it may concern:

Be it known that we, Henry E. Sachs and Peter F. Elzi, citizens of the United States, residing at Denver, in the county of Denver and State of Colorado, have invented a new, original, and ornamental Design for a Seal Press or Similar Article, of which the following is a specification, reference being had to the accompanying drawing, forming part thereof.

The figure is a perspective view of a seal press or similar article showing our new design, the opposite side of which presents substantially the same appearance as the side shown.

We claim:

The ornamental design for a seal press or similar article, as shown and described.

HENRY E. SACHS.

PETER F. ELZI.
